FLUE OVEN CLEANER

Frank J. Ayers, Piedmont, S. C.

Application December 14, 1936, Serial No. 115,857

1 Claim. (Cl. 126—17)

The present invention relates to new and useful improvements in flue or stove pipe ovens and has for its primary object to provide, in a manner as hereinafter set forth, novel means through 5 the medium of which soot and other accumulations may be expeditiously removed from the usual spaced walls of said oven.

Other objects of the invention are to provide a cleaner for flue or stove pipe ovens which will be 10 comparatively simple in construction, strong, durable, highly efficient and reliable in use, compact and which may be manufactured at low cost.

All of the foregoing and still further objects and 15 advantages of the invention will become apparent from a study of the following specification, taken in connection with the accompanying drawing wherein like characters of reference designate corresponding parts through the several views, and wherein:

20 Figure 1 is a view in side elevation of a flue oven equipped with a cleaner constructed in accordance with the present invention, said oven being broken away in section.

Figure 2 is a vertical sectional view, taken substantially on the line 2—2 of Fig. 1.

Figure 3 is a detail view in section through the cleaner.

Figure 4 is an elevational view of the cleaner.

Figure 5 is a detail view in vertical section 30 through one of the rod bearings mounted on the oven.

Referring now to the drawing in detail, it will be seen that the reference numeral 1 designates generally a flue oven which, as usual, comprises 35 spaced inner and outer annular walls 2 and 3, respectively, said walls being in the form of cylinders providing an annular heat chamber 4 for the passage of smoke and other products of combustion. An inlet 5 and an outlet 6, for connection with sections of a stove pipe, communicate 40 with the chamber 4.

The inner cylinder 2 provides a heating chamber 7 which is closed at its front by a door 8. A tapered end wall 9 closes the space between the 45 inner and outer cylinders 2 and 3 at the front of the oven. The rear end of the oven 1 is closed by a wall 10.

Mounted for sliding movement in the chamber 4 between the inner and outer cylinders 2 and 3 50 is a scraper 11 in the form of a flat ring of suit-

able metal. Fixed to diametrically opposite portions of the ring 11 and projecting horizontally therefrom are operating rods 12 which extend slidably through the end wall 10 and have fixed on their outer ends suitable knobs or handles 13. 5 Openings 14 in the end wall 10 (see Fig. 5) accommodate the rods 12. The rods 12 travel in bearings 15 which are fixed on the end wall 10 in alignment with the openings 14.

It is thought that the operation of the invention will be readily apparent from a consideration of the foregoing. When it is desired to remove soot or other accumulations from the walls of the annular chamber 4 it is only necessary to grasp the knobs or handles 13 and reciprocate 15 the scraping ring 11 in said chamber. Through the medium of the pair of rods 12 distortion and consequent binding of the annular scraping ring 11, should it encounter particularly hard deposits or accumulations, will be prevented. By the construction and arrangement it is thought that the entire wall area of the annular chamber 4 may be expeditiously and thoroughly cleaned with a few strokes of the scraping ring 11.

It is believed that the many advantages of a 25 flue oven cleaner constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed:—

35 In a flue oven of the type including spaced inner and outer cylinders providing an annular chamber, end walls closing the space between said cylinders at the ends thereof, one of said end walls having openings in diametrically opposite portions thereof, bearings fixed on said one end wall 40 in alignment with the openings, a substantially flat metallic ring mounted for reciprocation in the annular chamber and adapted to remove accumulations from the walls thereof, rods fixed on diametrically opposite portions of said ring and 45 projecting at right angles therefrom, said rods extending slidably through the bearings, and operating knobs fixed on the outer ends of the rods.
